US00D701948S

(12) **United States Design Patent**
Schliwa et al.

(10) **Patent No.:** US D701,948 S
(45) **Date of Patent:** ** Apr. 1, 2014

(54) **URINAL**

(75) Inventors: **Ralf Schliwa**, Dollern (DE); **Maria T. Strasdas**, Jork (DE); **Florian Schüphaus**, Hamburg (DE); **Christian Seibt**, Buchholz i.d. Nordheide (DE)

(73) Assignee: **Airbus Operations GmbH**, Hamburg (DE)

(**) Term: **14 Years**

(21) Appl. No.: **29/431,652**

(22) Filed: **Sep. 10, 2012**

(30) **Foreign Application Priority Data**

Mar. 9, 2012 (EM) 001317473

(51) **LOC (10) Cl.** **23-02**

(52) **U.S. Cl.**

USPC **D23/274**

(58) **Field of Classification Search**

USPC D23/302, 303, 274; 4/301, 663-665

See application file for complete search history.
